ADJUSTABLE DIE

Louis G. Freeman, Jr., Cincinnati, Ohio, assignor
to The Louis G. Freeman Company, Cincinnati, Ohio, a corporation of Ohio

Application September 19, 1941, Serial No. 411,572

11 Claims. (Cl. 164—93)

This invention relates to shoe machinery, and more particularly to improvements in dies for use in ornamenting shoe uppers and shoe parts by forming cutouts or perforations in portions thereof.

The illustrated embodiment of the invention is a type of die adapted for operations upon skins, upper blanks, fitted or closed uppers, and the like, by which markings may be applied to the work, at the same time, or as part of a cycle of operations, during which the work may also be ornamented by the perforating or cutting out of a design therein. Preferably the marking and perforating or cutting will be performed in a single machine operation, and the marking may take the form of printing with ink, or the application of a heated element, or the like.

Specifically this invention relates to improvements in dies of the general type disclosed in the patent to Benjamin W. Freeman, No. 2,244,613, dated June 3, 1941, and is well adapted to use in the type of machine disclosed in the patents to Benjamin W. Freeman, Reissue 20,294, dated March 16, 1937, and Reissue 21,321, dated January 16, 1940.

A problem arises in the use of these dies due to the fact that the work varies in size for a given run. Shoe parts are graded in accordance with the desired size of finished shoe, and the shoe upper parts will be ornamented in a series of different sizes and different widths of the same style. Because of the fact that the die must bear a fixed predetermined relation to the work, it is evident that as the size of the work varies, the relative position of the ornamentation in the work will vary accordingly, unless some means is provided to accommodate the die to the work.

Sometimes the shoe parts in the series have a common portion of their peripheries held to the same grade, this being known as center grading. At other times, where the parts in the series have no common portion in their peripheries, they will be regular graded. Still again there will be occasions when the parts in the series have a portion which is center graded, and other portions which are regular graded.

When dealing with this last type of series, it is customary to provide the die with a fixed group of ornamenting elements to ornament each shoe part in that portion of the series which is center graded, and with an adjustable ornamenting element or elements to ornament one or more of the different sizes which are regularly graded.

It has long been recognized as desirable to supplement the fixed or basic group of ornamenting

elements with auxiliary ornamenting elements in order to enlarge the ornamentation formed by the fixed group, from the smallest to the largest shoe part in the series. This has been effected in various ways, as by removable inserts which could be added or removed from the die structure when desired, or when feasible by providing relatively slideable die sections, adjustable to each other.

But such structures are in many instances cumbersome, expensive to manufacture, and in the case of removable inserts, require time and labor when it is desired to increase the size of an ornamental pattern to accommodate large sizes of a run of shoe parts.

A primary object of the present invention is to provide an arrangement in which the auxiliary ornamenting elements constitute a series of permanent parts of the die structure, any one or more of which may be thrown into and out of operating position at the will of the operator.

Another object contemplates a simplified structure in which the adjustable die elements may be moved into or out of operative position by the simple flick of a lever.

The illustrated embodiments may be constructed similarly to the dies illustrated in the patents above mentioned, with the exception of that portion of the die wherein the ornamenting elements are arranged for adjustment into and out of their cutting position.

For a more complete description of the invention, and to the attainment of the foregoing and other objects which will appear as the description proceeds, reference may be made to the accompanying drawings in which:

Fig. 1 is a plan view looking at the operating face of the die;

Fig. 2 is a front elevation thereof;

Fig. 3 is a section on the line 3—3 of Fig. 2 illustrating the plan of the back surface of the die.

Fig. 4 is an enlarged fragmentary detailed view showing the adjustable elements in elevation.

Fig. 5 is an enlarged vertical section through the center of the die structure.

Fig. 6 is an enlarged vertical section looking from the side of the front part of the die structure.

Fig. 7 is a perspective elevation of one of the auxiliary elements, and

Fig. 8 is a perspective elevation of one form of cam which may be employed.

Referring now more particularly to the drawings in which like reference numerals designate like parts, the die organization comprises gen-

erally a top or base plate 10, by means of which the die is secured into position in the ornamenting machine, and a die block 11 carried by the top plate 10, but spaced therefrom by a series of sleeves or struts 12 affording clearance for operating parts of the die unit mounted therebetween.

A tube or cutter plate 13 is secured to the die block 11, this plate 13 serving to rigidly mount the ornamenting tubes 14, or any other cutting and ornamenting instrumentalities which may be required by an individual pattern. Conventionally the tubes 14 are hollow and the die block 11 will be perforated, as indicated at 15 (Figs. 3 and 4) behind each tube to permit the escape of chips or cuttings removed from the work by the tubes.

To provide for variation in pattern, as well as to accommodate different shapes of work, it is desirable to interchange cutter plates, and to this end the plates 13 are arranged for ready detachment and replacement with respect to the die block 11. A simple form of latch, as illustrated in Figs. 1, 2 and 3 includes a pair of headed rivets or buttons 16—16 secured to the face of the plate 13 on the side thereof adjacent the die block 11, with their edges protruding beyond the edge of the plate 13, to form latch flanges. At one side of the plate 13, the block 11 is provided with an undercut keeper 17, beneath which the flange of one button 16 may be inserted. Adjacent the opposite edge of the plate 13 a latch arm 18 is eccentrically pivoted as at 19, such that it may be swung into position across the cooperating button 16, to latch the plate 13 in position. The die block 11, or the plate 13, or the latching members 17 and 18, may be suitably recessed as desired, to ensure a close fit of the plate 13 to the face of the block 11. A suitable ball detent 20, or any other equivalent stop means, may be provided in the latch arm 18 to ensure retention thereof in latching position.

Resiliently mounted stripper plates 21 carrying marking ribs or protuberances 22 are carried by the die normally in a plane slightly advanced with respect to the cutting edges of the tubes 14. These plates 21 are mounted upon studs 23 which extend through the die block 11 and the cutter or tube plate 13, and the heads 24 of which are conveniently arranged to ride telescopically within certain of the sleeves or struts 12. Springs 25 within the sleeves 12, abut the respective heads 24, and serve to normally maintain the plates in their outermost or projected position, and to exert such pressure as may be required for marking purposes. The strength of the springs 25 may be such, in some instances, as to exert stripping pressures upon the marking plate in a well-known and conventional manner, or if the die is constructed in accordance with the disclosures of the aforesaid patents, wherein stripping pressures are applied from sources extraneous to the die, the springs 25 may be made sufficiently light as to print without in any manner exerting an indenting pressure upon the work. The structure thus far described is more or less conventional in its nature, in that it is shown and illustrated in the patents to which reference has been made, and is in commercial usage today.

The strippers 21 are illustrated in the present embodiment as being attached by small screws to the studs 23, but they may readily be made attachable thereto by snap fasteners in the manner described and shown in the Freeman patent, No.

2,244,613. This arrangement would facilitate interchangeability of markers at any time that the tube plates are interchanged, it being obvious that the marker structure must conform at all times 5 both to the pattern and arrangement of tubes, although this object is by no means defeated in the use of removable screws in lieu of snap fasteners, or other attaching means.

The strippers, of course, are perforated or otherwise cut out, as indicated at 26 to permit the passage of the cutters or tubes 14 therethrough, and should anything occur to block these perforations, or for that matter should the marker plates in any manner require repairing or replacement, this is permitted by the detachable arrangement described above.

If the die is designed for use with an ornamenting machine or press which has means to apply stripping pressures to the die from a source externally of the die, then the studs 23 or heads 24 may be equipped with stems projectable beyond the normal confines of the die for purposes of receiving such stripping pressures, this arrangement also being described and shown in Freeman patent, No. 2,244,613.

The auxiliary cutting elements illustrated herein comprise a series of bars, each carrying tubes corresponding to the tubes 14, and a cam mechanism is provided for actuating the bars to bring them into operative alignment with the fixed cutters or tubes 14.

This cam mechanism may include a generally oval or elliptical plate 30 stepped transversely as at 31—31 to provide low points, having beveled or tapered surfaces as indicated at 32 and 33, to permit the low points to merge into the higher cam surfaces of the plate. The plate 30 is slotted longitudinally at 34 to enable the cam to slide along a pair of headed guide studs 35 and 36, mounted in the die block 11.

A bridge 37 may be mounted to extend laterally of the die block 11, across the cam plate 30, by means of spacers 38 and screw 39, affording necessary clearance for the cam and operating parts, and which, at the same time, serve to hold the cam in its operating positions. A primary purpose of this bridge, which of course is rigid with die block 11, is to serve as a mounting for the actuating mechanism, by means of which the cam is moved. This mechanism comprises an angle lever 40 pivoted at 41 to the bridge 37, and having its short arm 42 pivotally connected at 43 to a link 44 which in turn is pivoted at 45 to the cam plate 30. The long arm of the lever 40 terminates in a handle portion 46.

It follows that as the lever 40 is swung, by means of the handle 46, about the pivot 41, that the connections 42, 43, 44 and 45 will slide the cam plate 30 in one direction or another along the guide studs 35 and 36, thus shifting the stepped portions 31—31 of the plate 30. To facilitate adjustment, an arcuate end piece 47, notched as at 48, and calibrated as at 49, may be mounted on the front of the die; the handle 46 will be equipped with a leaf spring 50 mounting a pawl or detent 51 for engagement in the respective notches 48.

A pair of cam strips or gibs 52—52 are secured on the operating face of the die block 11, for the purpose of retaining auxiliary cutter elements in place in the die. These auxiliary cutter elements are illustrated herein as a series of composite bars 53 carrying cutters or tubes 54. Secured to each of the cutter bars 53 at the rear

thereof, is a cam bar 56, which is held in position by means of dowel pins 57, and a screw 58, this cam bar having its ends 59 projected beyond the ends of the cutter bar 53. The cam bars are perforated behind the tubes as indicated at 55, to permit the escape of cuttings or chips.

The composite cutter and cam bars 53—56 are mounted in the die unit with the cam portions engaging the cam plate 30, and the ends 59 extending over the gibs 52. The cutter bar portions 53, being shorter than the cam bar portions 56 may be proportioned to engage the sides or edges of the gibs 52 for guidance thereby into and out of position. Springs 60—60 are inserted between the ends 59 and gibs 52, both of which are suitably recessed to receive and retain the springs in position, and as clearly shown in Figs. 5 and 6, sufficient clearance is provided between the gibs 52 and the ends 59 to enable the composite bars to move into and out of an operative position. It will be noted from Fig. 6 that the normal or inoperative location of the composite cutter bars is in the stepped portion of the cam plate 30 with the cam bars 56 engaging the plate surfaces 31. When, however, the cam plate 30 is slid forwardly by means of the handle 46, the beveled portions 33 will engage the cam bars 56 which are also beveled or rounded along the edge 61, and the bars will be forced downwardly against the action of the springs 60, into a position where the tubes 54 are in the same cutting plane as the fixed tubes 14. Reversal of movement of the cam plate 30 permits the springs 60 to restore the bars one by one to their inoperative position.

Having thus described the invention, the operation thereof will be readily apparent.

The die may be secured in position in the ornamenting machine by any conventional means, the usual dove-tail strip 62 and locating lug 63 being conventionally provided for the purpose. For small sizes of work, the auxiliary elements or composite bars 53—56 will be out of the way resting in the stepped portion 31 of the cam plate 30. As the size of work increases, the cutter bars may be dropped one by one into cutting position, and held rigidly there by the cam plate 30.

Many modifications will occur to those skilled in the art, and it is intended that the foregoing embodiments be regarded as illustrative rather than as limiting.

From the foregoing it follows that the invention is just as applicable to a die which cuts or perforates without marking, and the invention is not in anywise to be limited to a combined cutting and marking die.

Again, the arrangement of the die may be such as to cut up instead of down; and quite obviously, the arrangement of tubes or cutters used as auxiliary elements may be varied to accord with the pattern desired. It is not essential that the composite, auxiliary cutter bars, illustrated above as carrying a single tube or two, be confined to this arrangement. Tubes may be distributed in a pattern on the individual bars, and the bars may be widened to accommodate same. Further, where the marker plates are illustrated herein as single units extending beyond that portion of the die block to which the tubes 14 are rigidly affixed, in order to accommodate the auxiliary tubes, such plates may readily be divided into separate parts, and those parts which would otherwise extend beyond the auxiliary elements be detached until such time as larger sizes in the run of work are encountered.

Having thus described my invention, what I claim as new and desire to secure by Letters Patent of the United States is:

1. A die unit for use in an ornamenting machine, comprising a base, work ornamenting means fixedly secured to said base, and work ornamenting means movably mounted on said base, the ornamenting portions of said fixed means being normally located in an operative zone, and the ornamenting portions of said movable means being normally located in an inoperative position, said movable ornamenting means comprising a plurality of auxiliary movable elements, and a common means to move said elements individually into and out of the operative zone of the ornamenting portions of the fixed means.
2. A die unit for use in an ornamenting machine, comprising a base, work ornamenting means fixedly secured to said base, and work ornamenting means movably mounted on said base, the ornamenting portions of said fixed means being normally located in an operative zone, and the ornamenting portions of said movable means being normally located in an inoperative position, said movable ornamenting means comprising a plurality of auxiliary movable elements, and a common means to move said elements one by one into the operative zone of the ornamenting portions of the fixed means, and to retract them in reverse order.
3. A die unit for use in an ornamenting machine, comprising a base, a cutting die fixedly secured to said base, and an auxiliary cutting die including a die block having a cutting element, movably mounted on said base, the cutting edge of said fixed cutting die being normally located in an operative zone and the cutting edge of said auxiliary cutting die being normally located in an inoperative position, and cam means cooperative with said die block to move the cutting edge of said auxiliary die into and out of said operative zone.
4. A die unit for use in an ornamenting machine, comprising a base, a cutting die fixedly secured to said base, and an auxiliary cutting die including a die block carrying a cutting element, and a cam bar secured to said die block, the cutting edge of said fixed cutting die being normally located in an operative zone, and the cutting edge of said auxiliary cutting die being normally located in an inoperative position, and a manually movable cam plate cooperative with said cam bar to move the cutting edge of said auxiliary die into and out of said operative zone.
5. A die unit for use in an ornamenting machine, comprising a base, a cutting die fixedly secured to said base, and an auxiliary cutting die including a die block carrying a cutting element, and a cam bar secured to said die block, the cutting edge of said fixed cutting die being normally located in an operative zone, and the cutting edge of said auxiliary cutting die being normally located in an inoperative position, a manually movable cam plate cooperative with said cam bar to move the cutting edge of said auxiliary die into and out of said operative zone, said cam plate having a recessed portion to receive the cam bar when the auxiliary cutting die is located in the inoperative position, and a surface adjacent the recessed portion effective to hold the auxiliary die in the operative zone, when the cam plate has been moved for this purpose.
6. A die for use in an ornamenting machine comprising a base, a cutter plate carrying cutter

elements, fixedly secured to said base, an auxiliary cutter block carrying a cutter element, movably mounted on said base, retaining means on said base limiting movement of said auxiliary block away from the base, and bridge means at the opposite side of the base from the retaining means effective to limit movement of the auxiliary block into the base, cam means interposed between the said auxiliary block and said bridge means, said cam means being shaped to engage and move said auxiliary block to an operative position in a direction away from said bridge means, and actuating means for said cam means carried by said bridge means and connected to said cam means.

7. A die for use in an ornamenting machine comprising a base, a cutter plate carrying cutter elements, fixedly secured to said base, an auxiliary cutter block carrying a cutter element, movably mounted on said base, retaining means on said base limiting movement of said auxiliary block away from the base, and bridge means at the opposite side of the base from the retaining means effective to limit movement of the auxiliary block into the base, cam means interposed between the said auxiliary block and said bridge means, said cam means being shaped to engage and move said auxiliary block to an operative position in a direction away from said bridge means, actuating means for said cam means carried by said bridge means and connected to said cam means, and means interposed between said retaining means and said auxiliary block to return said block to its original position upon movement of the cam means to an inoperative position.

8. A die unit for use in an ornamenting machine, comprising a base, work ornamenting means fixedly secured to said base, and work ornamenting means movably mounted on said base, the ornamenting portions of said fixed means being normally located in an operative zone, and the ornamenting portions of said movable means being normally located in an inoperative position, said movable ornamenting means comprising a plurality of auxiliary movable elements, a

cam plate, and means co-operative with said cam plate to move said elements individually into and out of the operative zone of the ornamenting portions of the fixed means.

5. 9. A die unit for use in an ornamenting machine, comprising a base, work ornamenting means fixedly secured to said base, and work ornamenting means movably mounted on said base, the ornamenting portions of said fixed means being normally located in an operative zone, and the ornamenting portions of said movable means being normally located in an inoperative position, said movable ornamenting means comprising a plurality of auxiliary movable elements, a cam plate, and means co-operative with said cam plate to move said elements one by one into the operative zone of the ornamenting portions of the fixed means, and to retract them in reverse order.
10. 10. A die unit for use in an ornamenting machine, comprising a base, a cutting die fixedly secured to said base, and an auxiliary cutting die including a die block having a cutting element, movably mounted on said base, the cutting edge of said fixed cutting die being normally located in an operative zone and the cutting edge of said auxiliary cutting die being normally located in an inoperative position, a cam plate, and means co-operative with said cam plate to move said auxiliary die into and out of said operative zone.

15. 11. A die unit for use in an ornamenting machine, comprising a base, and a plurality of cutting elements fixedly secured to said base, a die block movably mounted on said base and carrying an auxiliary cutting element, the cutting edges of said fixed cutting elements being normally located in an operative zone, and the cutting edge of said auxiliary cutting element being normally positioned by its die block, in an inoperative zone, a cam plate, and means cooperative with said cam plate to move said die block so as to position said auxiliary cutting element into and out of said operative zone.

LOUIS G. FREEMAN, JR.
